ELECTRIC IRON

Richard R. Fitzsimmons, Chicago, Ill., assignor
to The Hoover Company, North Canton, Ohio,
a corporation of Ohio

Application March 28, 1951, Serial No. 218,044

6 Claims. (Cl. 38—77)

1

This invention relates to electric irons and more particularly to an electrically heated steam iron which is readily convertible to dry ironing.

The present invention relates more particularly to a readily replaceable steam generating and distributing vessel for a steam iron designed as a replacement part for replacement by servicemen when the interior of the vessel becomes encrusted with lime deposits during use. The vessel of the present invention includes superheating passages and traps in which any unevaporated water leaving the flash boiler proper is evaporated so that dry superheated steam is supplied to the ironing surface of the iron.

Most tap water contains salts such as calcium salts which, when the water is evaporated, are deposited on the surface of the boiler and steam passages. In the steam iron, by the continued use of calcium containing water, the flash boiler and steam passages will eventually become coated with lime deposits to such an extent that the passages will eventually become clogged, if not periodically cleaned. In addition, the coating of lime deposits in the boiler acts as a heat insulator and retards the transfer of heat from the heater to the water in the boiler which results in a marked decrease in efficiency of the iron.

According to the present invention the boiler and steam passages are readily separable from the iron proper so that when excessive lime deposits have formed the boiler may be readily replaced and the old one discarded or reconditioned for reuse.

The flash boiler of the present invention, while readily removable for replacement, is in direct heat exchange relationship with the heater which is embedded in the sole plate. The sole plate is preferably made of aluminum and the bottom of the boiler in heat exchange relationship therewith may be made of any good heat conducting material which may be readily cast or stamped to its exact dimensions by mass production methods.

According to the present invention the flash boiler including the steam passageways is positioned on top of the normally hot upper surface of the sole plate which results in three important advantages.

First, there are no steam passages between the heater and the ironing surfaces so that the heat flow path from the heater to the ironing surface is the same whether the iron is used dry or as a steam iron.

Second, the heat normally radiated upwardly

2

and wasted is utilized in producing and superheating steam.

Third, the boiler is positioned between the sole plate proper and the water reservoir to isolate the latter from the heat of the sole plate by a layer of steam when the iron is used as a steam iron and by an air chamber when the iron is used as a dry iron.

According to another feature of the present invention, the handle and the water reservoir are readily removable as a unit to provide for the ready removal of the vessel from the sole plate. The bolt which holds the handle reservoir assembly to the sole plate maintains a tight joint between the valve assembly and the duct leading directly to the flash boiler proper.

According to another feature of the present invention, the cover plate for the boiler proper is made of poor heat conducting material so that the upper surface of the boiler will be substantially below the temperature of the steam passing through the passageways therein to further isolate the water reservoir from the heat of the sole plate.

Other objects and advantages of the present invention will become apparent when taken in connection with the accompanying drawings in which:

Figure 1 is a side view of an electric iron, partially in section, showing the present invention.

Figure 2 is a sectional view taken on line 2—2 of Fig. 1, looking in the direction of the arrows; and

Figure 3 is an exploded view of the replaceable vessel of the present invention.

In the drawings, the reference numeral 10 represents the sole plate proper which may be made of aluminum and having a metal encased heater 11 cast therein preferably in a rib 12 extending upwardly from the upper surface of the sole plate. The heater 11 is of general U-shape, having its bight or nexus adjacent the toe of the iron and its legs extending backwardly to the rear of the sole plate adjacent the opposite side edges thereof.

The reference numeral 14 generally represents the replacement vessel of the present invention. It comprises a disc shaped bottom part 15 and an inner separator 23 which may be brazed, welded, or otherwise secured together. The two parts 15 and 23 are preferably made of good heat conducting metal such as aluminum, copper, brass or bronze.

The bottom part 15 has an upwardly extending bulge 16 in its bottom of a shape and size

to closely fit in good heat exchange relationship with the rib 12 in which the heater 11 is embedded, and an upwardly extending side wall 17 to which rear and front clamping lugs 18 and 19 are brazed, soldered, or otherwise secured. The rear lug 18 fits beneath the spring element 20 screwed or otherwise secured to the sole plate 10 and a clamping clip 21 fits over the front lug 19 to clamp the boiler 14 tightly to the sole plate 10, by means of the screw 22.

The separator 23 comprises a U-shaped wall 24 spaced from the wall 17 of the bottom part 15 to form a pair of steam distributing ducts 25, the bottom part 15 being provided with openings 26 communicating with steam discharge ports 26' extending through the sole plate 10 to the ironing surface thereof and with ducts 25. While the ducts 25 have been shown connected at their front ends it is within the purview of this invention to form them as separate ducts.

Welded, brazed or otherwise secured to the inner surface of the wall 24 and to the bottom of the part 15 are a plurality of staggered baffles 27 having their alternate ends spaced from the wall 24 to form a tortuous steam superheating passage 28 and at the front a flash boiler proper 29. The rear ends of the legs of the wall 24 are cut away at 30 and 31 to form passages which connect the superheating passage 28 with the distributing ducts 25. It is to be noted that at the ends of baffles 27 the superheating passage 28 passes directly over the bulge 16 which is in direct heat exchange relationship with the heater, the end of the baffles being cut away to interfit with the bulge 16. It is also noted that the bulge 16 forms traps at the ends of the juxtaposed passages formed by baffles 27 so that any unevaporated water reaching those points will be trapped and evaporated the bulge 16 being in direct heat exchange relationship with the heater 11.

A cover plate 32, made of poor heat conducting material such as hard rubber, "Bakelite" or stainless steel, is bolted to the flange 33 of bottom part 15 by bolts 34. A sealing gasket 35 of cork or other suitable heat resistant material is positioned between the mating surfaces of the flange 33 and cover plate 32, it being noted that the baffles 27 extend above the surface of the flange 33 in order to compensate for the space occupied by the gasket 35.

The cover plate 32 is provided with an opening 36 immediately above the flash boiler 29. At its upper end the opening 36 is of tapered formation as indicated at 37 to cooperate with the tapered lower end 38 of a valve body 39, a conical heat resistant gasket 40 being interposed between the two surfaces.

The valve body 39 is suitably secured in an opening in the bottom wall of a water reservoir 41, held by brackets 42 and 43, beneath a cover shell 44 which extends downwardly about the peripheral edges of sole plate 10. The reservoir 41 is provided with an upwardly extending dome 45 surrounded by a compression spring 46 fitting between the lower wall of an upwardly extending protuberance 47 in cover shell 44 and the top of the reservoir 41 to normally hold the mating surfaces 37 and 38 against the gasket 40 when the iron is assembled.

A valve stem 48, adapted to close the opening 49 in valve body 39, is housed within a valve stem housing 50 suitably secured to dome 45 as by a clamping nut 51. The valve stem 48 may be screw threaded to the interior of the housing 50

in a manner well known in the art and is provided with an operating knob 52 by which the valve stem 48 may be adjusted relative to the opening 49 in the valve body 39 or may be seated in that opening to close off communication between the reservoir 41 and the flash boiler 29 when the iron is to be used as a dry iron. The valve stem 48 is also adjustable relative to its valve seat to control the rate of flow of water to the flash boiler 29 when the iron is used as a steam iron.

A handle 53, having a hollow front leg 54, to receive the valve stem housing 50 and the knob 52 and a rear leg 55 is secured to the cover shell 44 by brackets 56 and 57, the former extending upwardly into the recess in the front leg 54 and the latter extending upwardly into a recess in the rear leg 55.

The cover shell 44 is extended rearwardly beyond the sole plate 10 at 58, which extension cooperates with the top rear 59 of handle 53 to form supports upon which the iron may be supported on its heel when not in use. The knob 52 and valve stem 50 are of hollow formation and the interior of the latter communicates with the interior of the reservoir 41 so that water can be poured into the reservoir when the iron is resting on the sole plate 10. The arrangement is such that the opening 49 will be above the water level in the reservoir 41 when the iron is tipped backwardly on its heels on supports 58 and 59 when not in use.

Electricity is supplied to the heater 11 by conductor cords 60 which extend through the rear leg 55 of handle 53 in a manner well known in the art. The cords 60 are attached to terminals 61, one of which is connected to one end of the heater resistance and the other to a temperature control thermostat 62, the other end of which is connected to the other end of the heater resistance. The terminals 61 are clamped in place by a bracket 63 having an upwardly extending support 64 to which the rear of the cover shell 44 is attached by means of screw 65. At its midpoint the cover shell 44 is secured to a post 66 extending upwardly from the sole plate 10 by means of a screw 67. A closure plate 68 is attached to the extension 58 of the cover shell by a screw 69 to provide access to terminals 61. A control shaft 70 extends upwardly through an opening in the cover shell 44 and has a control knob 71 detachably secured thereto.

While the boiler 14 has been shown as extending backwardly to adjacent the post 66 it is to be understood that it may be extended backwardly along each side of the post and along each side of the thermostat 62. It may also be provided with an opening through which the post 66 extends.

60 Assembly and disassembly

The sole plate is cast with the heater 11 embedded in the rib 12, the discharge ports 26' drilled and the ironing surface of the sole plate polished. The control thermostat 62, control shaft 70, terminals 61, bracket 63 and post 66 are then assembled to the sole plate 10. As a separate operation the boiler 14 is formed as previously explained and the gasket 35, and cover plate 32 assembled thereto. The valve body 39, valve stem housing 50, valve stem 48 are assembled to the reservoir 41. The end 60 of conductor cord is assembled to a rear leg 55 of handle 53. The cover shell 44 is secured to the front and rear legs 54 and 55 of handle 53 by brackets 56

and 57. The spring 46 is assembled over dome 47, the reservoir 41 positioned within the shell 44 with the dome 45 and valve stem housing 50 extending upwardly into the hollow front leg 54 of the handle and secured thereto by brackets 42 and 43, the arrangement being such that the spring 46 presses the front end of the reservoir 41 downwardly against the bracket 43. The boiler 14 is then attached to the sole plate 10 by the brackets 20 and 21.

The handle-cover shell-reservoir assembly is then assembled over the sole plate-boiler assembly by applying the screws 65 and 67 which will cause the spring 46 to press the reservoir 41 downwardly and make tight contact between the conical opening 37 and the conical valve body 39, the gasket 40 being interposed therebetween. The cover plate 68 may then be assembled by screw 69 after the connections have been made between the cord 60 and the terminals 61. The control knobs 52 and 71 are then applied to the valve stem 48 and to the control shaft 70, completing the assembly.

To remove the boiler assembly 14 for replacement it is only necessary to detach control knobs 52 and 71, remove screws 65, 67 and 69 and tilt the handle-cover shell-reservoir assembly backward to expose the boiler 14 which may then be easily removed by detaching the clip 21 and sliding the boiler assembly forward from beneath the clip 20.

Operation

With the iron resting on the sole plate and the valve stem 48 closed against its seat, water may be supplied to the reservoir 41 by pouring it through the hollow control knob 52 and valve stem housing 50, it being noted that the outlet from the hollow valve stem 50 to the interior of the reservoir 41 is such that the quantity of water which may be poured into the reservoir 41 is limited so that the water level will be below the opening 49 when the iron is tilted rearwardly on the supports 58 and 59.

If the iron is to be used as a steam iron, the control knob 52 is adjusted so that the valve is opened the proper distance to supply the proper quantity of steam for the fabric being ironed and the control knob 71 adjusted to the proper temperature for that fabric. When the iron is tilted forwardly on the sole plate water will automatically drip into the flash boiler 29 and be flashed into steam which will flow backwardly through the superheating passageways 28 between the baffles 27, outwardly through the openings 39 and 31 into the steam ducts 25 and through the openings 26 and 28' to the fabric being ironed.

Any water which may perchance leave the flash boiler 29 proper will be trapped in the superheating passage 28 by the upwardly extending humps 16 which form traps at the end of each passage formed by baffles 27.

When the iron is not being used it is usually tilted backwardly upon the supports 58 and 59 and the flow of water to the flash boiler 29 will be automatically terminated since the level of the water in the reservoir 41 will be below the opening 49.

When it is desired to use the iron as a dry iron the control knob 52 is operated to close the valve to completely shut off the flow of water to the flash boiler 29 and the thermostatic control knob 71 adjusted to the proper temperature for the fabric to be ironed.

From the foregoing it can be seen that this in-

vention provides a simple replaceable vessel for a steam iron which can be easily replaced by a new one and the old one discarded or reconditioned for reuse. Additionally, the handle-cover shell-reservoir assembly is such that a sealing contact is automatically made between the valve body and the opening in the cover plate leading to the flash boiler proper by the mere attachment of that assembly to the sole plate. By such an arrangement no lifting stress is applied to the boiler proper as the iron is moved about.

While I have shown and described but a single embodiment of my invention it is to be understood that that embodiment is to be taken as illustrative only and not in a limiting sense. I do not wish to be limited to the particular structure shown and described but to include all equivalent variations thereof except as limited by the scope of the claims.

I claim:

1. In an electric iron; a sole plate; a U-shaped heating element embedded therein; said sole plate having an upwardly extending land above said heating element and being formed with steam emitting openings therethrough between said land and the lateral edges thereof and a detachable steam generating and distributing vessel detachably secured to the top of said sole plate, said vessel being formed with a flash boiler in intimate heat exchange relationship with said land at the bight or nexus of said heating element, steam distributing ducts connecting said flash boiler to said steam emitting ducts, a water reservoir supported above said vessel and a valved opening formed in the bottom of said reservoir above said flash boiler for controlling the flow of water thereto.

2. In an electric iron according to claim 1 in which said land forms a depressed portion centrally of said sole plate and a depressed portion over said steam emitting openings and said steam generating and distributing vessel interfits with said depressed portions and land in such a manner that said steam distributing ducts are in heat exchange relationship with the inner, top and outer sides of said land.

3. In an electric iron according to claim 1 including a separator within said steam generating and distributing vessel dividing said element into a front flash boiler proper, a tortuous superheating passage extending rearwardly from said flash boiler and steam conveying ducts between said separator and the outer walls of said vessel and communicating with the rear ends of said superheating duct.

4. In an electric iron, a sole plate, a heating element therefor, a steam generating and distributing vessel detachably secured to said sole plate in heat exchange with said heating element, a flash boiler formed in said vessel, and a handle-cover shell-water reservoir assembly detachably secured to said sole plate independently of said vessel, said vessel and reservoir having mating water delivering connections above said flash boiler which are held in mating relationship when said handle-cover shell-water reservoir assembly is attached to said sole plate.

5. In an electric iron according to claim 4 including spring means for holding said water delivering connections in mating relationship when said assembly is attached to said sole plate.

6. A steam generating and distributing vessel for detachable connection to the sole plate of an electrically heated iron comprising, a dish shaped bottom member having its lower surface formed

to interfit with the top surface of said sole plate, a separator interiorly of said bottom member, said separator including a U-shaped wall spaced from the side walls of said bottom member to form a pair of forwardly extending steam conducting passages and staggered transversely extending walls forming a front flash boiler and a rearwardly extending tortuous steam superheating passage communicating at its rear end through said U-shaped wall with said forwardly extending steam conducting passages and a cover plate detachably secured to the open top of said vessel and overlying said flash boiler and said steam passages.

RICHARD R. FITZSIMMONS. 15
